(No Model.)

S. W. BRACKETT.

MAIL SACK TAG.

No. 298,345.

Patented May 13, 1884.

UNITED STATES PATENT OFFICE.

SEWARD W. BRACKETT, OF EAU CLAIRE, WISCONSIN.

MAIL-SACK TAG.

SPECIFICATION forming part of Letters Patent No. 298,345, dated May 13, 1884.

Application filed October 15, 1883. (No model.)

To all whom it may concern:

Be it known that I, SEWARD W. BRACKETT, a citizen of the United States, residing at Eau Claire, in the county of Eau Claire and State 5 of Wisconsin, have invented certain new and useful Improvements in Mail-Sack Tags, of which the following is a specification, reference being had therein to the accompanying drawings.

10 My invention relates to tags for mail-sacks; and it consists in the parts which will be hereinafter described, and pointed out in the claim.

In the accompanying drawings, Figure 1 is a perspective view of the top part of a mail- 15 sack provided with my improvement. The neck of the sack in this view is provided with a circular row of openings through which a cord is tightly drawn and tied. The tag is secured to the cord by means of the double hook. Fig. 2 is a perspective view of the tag and hook. Fig. 3 is a cross-section of the tag and the inclosed pasteboard strip, upon which may be written the name of the post-office for 20 which the sack is destined. Fig. 4 is a front view of the hook detached from the tag.

In the accompanying drawings like letters indicate like parts in the several views.

A is the body or back of the tag proper, and A' A' are two side flanges thereof. These 30 flanges fold over the face of the tag, whereby side grooves are formed for the reception of the removable pasteboard strip upon which the inscription is placed.

A² A² are the lower ends of the flanges A' A'. Said lower ends are bent down to the face of 35 the back piece, A, to prevent the pasteboard or card D from slipping out the bottom of the tag.

B is a flange on the lower end of the back 40 piece, A, upon which the bottom end of the card D rests. The bottom end of the tag may be closed in several ways. The bottom of the piece A may be constructed with a short projection adapted to fold under the bottom of 45 the flanged ends A²; or the flange B may be dispensed with and the ends A² turned in against the face of the back piece, A, thereby preventing the card D from passing through the grooves formed by the side flanges.

C represents an opening in the back piece, 50 A, in which the loop E' of the double hook E is secured.

E² E² are two oppositely-projecting hooks formed integral with loop E'.

E³ E³ are outwardly-projecting arms on the 55 hooks E². The arms E³ are bent outward to permit the hook to readily engage and straddle the cord. The two hooks lie sufficiently close to each other to snugly embrace the average cord when the device is being engaged or 60 disengaged. This arrangement serves to prevent the cord and hook from accidental disengagement.

F is a tie-cord drawn down through the openings in the neck of the sack, and F' is the knot 65 of said cord.

G represents the sack.

The hook E is preferably made of resilient metal. The name of the post-office for which the sack is intended is written upon the card 70 D. Said card should be of a flexible nature, and of dimensions adapted to fit within the grooves formed by the flanges A'. When the card is once in its case, or within the grooves, it cannot be displaced by any movement of 75 the tag. The ends A² of the side flanges (or the bottom flange, B) prevent the card from passing downward, and it cannot work out at the top, inasmuch as the ring or loop E' operates as a stop for the card. The card may, however, be drawn out of the top by hand; but it cannot be displaced by any action or position of the tag.

In attaching the device to a cord the operation is as follows: One of the arms E³ is drawn 85 down over the cord to be engaged, and then the cord placed into the notch of the hook. The hook is then turned half-way around and pressed upward, admitting the cord down the inner side of the opposite hook, whereby the 90 arm on said opposite hook is raised over the cord, and the cord thereby secured by both hooks. By reversing the operation the hooks may be disengaged. It requires but an instant to engage or disengage the hook by hand. It 95 is simple and certain in its operation, and will not become detached by any action of the tag.

I attach importance to the fact that the loop

E' of the hook performs the double function as an attachment for the eye e of the tag, and also prevents the card from slipping out of the tag by means of the top portion of said card 5 abutting against the under surface of said loop.

Having thus described my invention, I claim as new and desire to secure by Letters Patent—

In a mail-sack tag, a body provided with side flanges turned over, whereby side grooves are 10 formed for the reception and retention of the card, the lower end of said body being provided with a suitable stop or bottom rest for

the card, the upper end of said body having an opening, in combination with a hook having a loop, said loop being secured in said opening, and forming a top stop to prevent the displacement of the card, as specified. 15

In testimony whereof I affix my signature in presence of two witnesses.

SEWARD W. BRACKETT.
